Patented Nov. 11, 1975

237,567

COCKTAIL TABLE

Norman C. Korn, 1337 E. 80th St.,
Brooklyn, N.Y. 11236

Filed May 28, 1974, Ser. No. 473,753

Term of patent 7 years

Int. Cl. D6—03

U.S. Cl. D6—179

Fig. 1

Fig. 4

Fig. 2

Fig. 3

Fig. 5

FIG. 1 is a perspective view showing my design for a cocktail table.

FIG. 2 is an elevational view of one side thereof; the other side being identical.

FIG. 3 is an elevational view of one end thereof; the other end being identical.

FIG. 4 is a top plan view thereof; and

FIG. 5 is a bottom plan view thereof.

I claim:

The ornamental design for a cocktail table, substantially as shown and described.
